Primary Examiner — Richard E Chilcot(57) **CLAIM**

The ornamental design for a garbage container, as shown and described.

DESCRIPTION

FIG. 1.1 is a perspective view showing my new design of a garbage container;

FIG. 1.2 is a side elevational view of the garbage container of FIG. 1.1, the opposing elevational view being a mirror image thereof;

FIG. 1.3 is a front elevational view of the garbage container of FIG. 1.1, the opposing rear elevational view being a mirror image thereof;

FIG. 1.4 is a top plan view of the garbage container of FIG. 1.1;

FIG. 1.5 is a perspective view of the garbage container of FIG. 1.1 with the lid rotated approximately 180 degrees about its axis;

FIG. 1.6 is a perspective view of the garbage container of FIG. 1.5 with the container rotated approximately 45 degrees; and

FIG. 1.7 is a perspective view of the garbage container of FIG. 1.1 with the container rotated approximately 90 degrees.
